ATTORNEY

UNITED STATES PATENT OFFICE.

HENRY HEILBRONNER AND HENRY A. ROSBACK, OF SPRINGFIELD, ILLINOIS.

BARREL-STAND.

SPECIFICATION forming part of Letters Patent No. 317,133, dated May 5, 1885.

Application filed February 18, 1885. (No model.)

To all whom it may concern:

Be it known that we, HENRY HEILBRONNER and HENRY A. ROSBACK, citizens of the United States, residing in Springfield, in the county 5 of Sangamon and State of Illinois, have invented certain new and useful Improvements in Barrel-Stands, of which the following is a specification, reference being had to the accompanying drawings.

10 This invention has relation to that class of barrel-stands which are adapted to be arranged beneath and connected with a counter, and to permit of the swinging or drawing of the barrel from under the same for access to 15 remove its contents; and the invention consists in certain features of construction hereinafter described, and specifically set forth in the claims.

Referring to the drawings, Figure 1 is a side 20 elevation of a stand, a barrel thereon, and a section of the floor and counter. Fig. 2 is a perspective of the principal element of the stand. Figs. 3 and 4 are a perspective and a central vertical section, respectively, of the 25 upper end of the standard; and Fig. 5 is a side elevation of the lower end of said stand and sections of adjacent parts.

Like letters indicate like parts in all the 30 figures.

The standard A is preferably, though not essentially, square in cross-section throughout its length, and is provided at each end with a pivot or gudgeon.

B is a metal bearing-block seated within 35 the floor, so that its upper surface is flush therewith, and B' is a similar block set in flush with the under surface of the counter. As illustrated in Fig. 1, the socket of the block B' is sufficiently deep to permit the standard 40 A to be raised vertically until its lower pivot, A', is freed from the block B. In this manner the standard may be placed in position or removed, if desired.

In Figs. 3 and 4 I illustrate a preferred construction, in that the pivot A' is adapted to 45 reciprocate longitudinally within a recess, A², within which is arranged at the lower end of the pivot a coiled spring, A³, which, by means of the pivot and its thumb-piece A⁴, may be 50 compressed, in order that the pivot may be forced downwardly within the standard to permit the latter to be removed from its op-

erative position. By the preferred construction the standard may extend upward against the under surface of the counter to provide a 55 support for the same at the point where the stand is placed.

The stand proper consists of an integral casting, the base C of which is apertured at C' to receive the square standard A, and is 60 adapted to come directly in contact with the metal box B, whereby, as at this point a large portion of the weight of the barrel and its contents is supported, undue wear of the floor itself is avoided. From the base of the stand proper is extended an arm, C², which at 65 its end is vertically slotted for the reception of a roller, C³. From the arm C² are extended laterally integral arms C⁴, the upper surfaces of which are flush with that of the main arm 70 C². A sliding hook, D, shaped to embrace the upper end of the barrel at its chine, and formed as a part of the collar D', which is 75 adapted to fit the square standard A, is provided for the purpose of maintaining a barrel in position upon the stand. The collar D' and its hook, by reason of its capability of sliding from the top toward the bottom of the standard, is capable of being used with barrels or other packages of varied heights. 80

This being the construction, the operation is as follows: The stand being swung from under the counter, and having a base adapted by its square aperture to the square standard, rotates the standard, so that the hook D is 85 brought from a position beneath the counter to that wherein it is readily accessible for adjustment. The barrel being placed upon the stand, the collar is moved downwardly upon the standard until the hook embraces the upper end of the barrel, as shown, when the barrel and stand are swung beneath the counter, the roller C³ reducing the friction, and the metal bearing B also serving the same purpose. 90

Having described our invention, what we claim is—

1. In a barrel-stand of the class described, the base C, adapted to embrace a standard and provided with integral arms C² C⁴ and with 100 a roller, C³, substantially as shown and described.

2. In a barrel-stand, the combination, with the counter and with the standard of the bar-

rel-stand, of a reciprocatve spring-seated pivot, substantially as specified.

3. In a barrel-stand of the class described, the combination, with the standard having a lower rigid pivot and an upper longitudinally-reciprocatve pivot, of bearing-blocks arranged in a vertical line with each other in a counter and in a floor beneath the same, substantially as specified.

In testimony whereof we affix our signatures in presence of two witnesses.

HENRY HEILBRONNER.
HENRY A. ROSBACK.
